(57) **CLAIM**

The ornamental design for a modular charging station as shown and described.

DESCRIPTION

1. Modular charging station

1.1 is an exploded view of a charging station;

1.2 is a perspective view of a first configuration of charging station;

1.3 is a perspective view of a second configuration of the charging station shown with 4 long pegs omitted and 1 additional short peg;

1.4 is a side elevation view of a third configuration of the charging station;

1.5 is a side elevation view of that shown in 1.2;

1.6 is another side elevation view of that shown in 1.4;

1.7 is a perspective view of that shown in 1.4, shown in a state of environmental use.
